TRANSPARENCY FILM VIEWER

Jack W. Olsen, Santa Ana, Calif., assignor to
Mario N. Tartoglio

Filed July 22, 1963, Ser. No. 75,901

Term of patent 14 years

(Cl. D61—1)

FIG. 1 is a top front isometric view of a transparency film viewer showing my new design;

FIG. 2 is a top rear isometric view thereof;

FIG. 3 is a front elevational view thereof;

FIG. 4 is a left-side elevational view thereof;

FIG. 5 is a rear elevational view thereof;

FIG. 6 is a right-side elevational view thereof;

FIG. 7 is a top plan view thereof; and

FIG. 8 is a bottom plan view thereof.

I claim:

The ornamental design for a transparency film viewer, substantially as shown.
